UNITED STATES PATENT OFFICE.

JOHN E. RICHARDS, OF PECKVILLE, PENNSYLVANIA.

COMBINED SHINGLE SUPPORT AND CORNICE-PROTECTING DEVICE.

Application filed July 27, 1926. Serial No. 125,267.

This invention relates to a combined shingle support and cornice protecting device.

As is well known, the composition shingle now in common use is very flexible, and is not self supporting as is the wooden or metallic shingle. With the old type of roofing, using wooden, slate or metallic shingles, the last shingles were laid so as to extend somewhat beyond the edge of the cornice, to protect the same from the weather. When composition shingles, or shingles of flexible material are used, it has been the practice to lay them only as far as the cornice, and to apply wooden or other stiff shingles over the overhanging portion.

According to my invention I have provided a metallic strip which is laid along the edge of the roof and is provided with a flange which projects downwardly to cover the cornice, and protect the same from the weather, and is also provided with an overhanging portion having an upturned flange adapted to support the flexible shingles, and to hold the same in position.

This invention will be more fully understood by reference to the accompanying drawing in which is shown an illustrative embodiment of the invention.

In the drawings:

Fig. 1 is a perspective view showing a portion of a roof provided with my improved device.

Fig. 2 is a perspective view showing the combined shingle support and cornice protector, separate from the roof.

Fig. 3 is a view partly in elevation and partly in section showing the method of attaching the device to the roof.

Fig. 4 is an end view of the device, as applied to a roof.

As shown, the reference numeral 10 denotes a roof of a building, having a cornice or overhanging portion 11 projecting beyond the sidewall 12 of a building. Upon the roof are secured shingles 13, the last row of which extend beyond the edge of the roof and beyond the cornice as shown at 14.

My improved device is shown in detail in Fig. 2 and consists of a flat metal sheet, which is provided with a downwardly extending flange 16, formed by means of a double bend in the sheet, this flange serving to protect the edges of the cornice. Beyond the flange 16 is another flat portion on the same plane as the sheet 15, which, when

applied to the roof, projects beyond the cornice. At the extremity of the portion 17 there is an upturned flange 18 having an inverted flange 19 at the upper portion thereof. Preferably a plurality of spaced apertures 20 are provided at the base of the upturned flange 8.

In operation the metallic sheet 15 is secured to the roof 10 by means of suitable fastenings 21, before the shingles are applied. The downturned flange 16 abuts against the edge of the cornice 11, and the portion 17 projects beyond the edge of the roof, thus protecting the same against the weather.

The upturned portion 18 serves as a guide for the edge of the shingles when they are laid. The roofing is now applied, the shingles at the edge of the roofing extending beyond the roof and being supported by the metallic flange 17, and limited by the upturned flange 18. The rearwardly extending flange 19 may now be bent down upon the shingles, by hammering or otherwise, and thereby prevent the same from being blown or loosened by the wind. The holes 20 are for the purpose of preventing water from accumulating within the trough formed by the flanges 17, 18 and 19.

My improved device possesses the combined functions of a support for the shingles, a protection for the same against wind, a cornice protecting strip and provides in addition a decorative or ornamental finish for the edges of the roof.

This invention has been described in detail for the purpose of illustration, but is to be limited only by the appended claims.

It will be understood that the invention is applicable to the protection of the eaves as well as the cornice of the roof, although illustrated particularly with reference to the cornice.

What I claim is:

1. In combination with a roof and cornice, a shingle support comprising a metallic plate having integrally formed therefrom a portion adapted to be fastened to the roof in some suitable manner, a downwardly extending flange adapted to abut against the edge of the cornice, a section for projecting beyond the edge of the roof thus protecting the roof against adverse weather conditions, an upwardly extending element along the outer edge of the section adapted to serve as a guide for the edge of the shingles as they

are laid, an inwardly extending clinching portion along the upper edge of the element for the purpose of securely holding the shingles in position, the section, clinching portion and element being formed approximately at right angles to each other.

2. In combination with a roof and cornice, a shingle support comprising a metallic plate having integrally formed therefrom a portion adapted to be fastened to the roof in some suitable manner, a downwardly extending flange adapted to abut against the edge of the cornice, a section for projecting beyond the edge of the roof thus protecting the roof against adverse weather conditions,

an upwardly extending element along the outer edge of the section adapted to serve as a guide for the edge of the shingles as they are laid, an inwardly extending clinching portion along the upper edge of the element for the purpose of securely holding the shingles in position, the section, clinching portion and element being formed approximately at right angles to each other, and means for allowing the water to drain from the shingle support consisting of a plurality of openings along the lower edge of the element.

In testimony whereof I affix my signature.
JOHN E. RICHARDS.
